SWINGABLE JAW WRENCH

Victor S. Lundell, Jamestown, N. Y.

Application February 17, 1950, Serial No. 144,623

6 Claims. (Cl. 81—91)

1

This invention relates to an improvement in wrenches and particularly to that type of wrench required to grip and turn round or irregular shaped parts.

More specifically, the invention is directed to a wrench having a pair of jaws relatively movable about fixed axes so as to securely grip and turn or rotate a round or irregular shaped part. Such wrenches find particular application of use by plumbers who are required to have tools which will grip round pipe, irregular shaped couplings, plugs, caps, etc., and rotate such parts to effect threaded engagement or disengagement with respect to other parts.

An object of the invention lies in the provision of a plural jaw wrench in which a bodily movable jaw may swing about a pivot into or out of proximity with another jaw, that takes the form of a toothed wheel rotatable about a fixed pivot.

A further object of the invention lies in the provision of a wrench in which a gear connection is provided for effecting rotation of a fixed pivot, toothed jaw by the pivotal movement of another jaw.

Another and further object of the invention lies in the provision of a wrench in which the gear connection between a rotatable fixed pivot jaw or wheel and a swingable jaw may be released to enable free rotation of the wheel to present different teeth for cooperation with the teeth of the swingable jaw.

Other and further objects of the invention will be more fully understood from a consideration of the following specification, taken in conjunction with the accompanying drawings; and in which:

Fig. 1 is a side elevational view of a wrench embodying one form of the invention;

Fig. 2 is a front elevational view of the structure shown in Fig. 1;

Fig. 3 is a rear elevational view of the structure shown in Fig. 1;

Fig. 4 is a fragmentary side view of a portion of the wrench, parts being broken away to show the relative positions of the jaws when in operative engagement with a tubular part;

Fig. 5 is a view similar to Fig. 4, showing the jaws in fully opened position, with the gear connection therebetween rendered inoperative and a spring in dead center position;

Fig. 6 is a fragmentary side view of a modification, parts being broken away to show a rotatable pivot jaw and its connection with a swingable jaw;

Fig. 7 is a fragmentary front elevational view of the modification shown in Fig. 6; and

2

Fig. 8 is a fragmentary rear elevational view of the modification of Fig. 6.

Referring more particularly to the drawings, the reference numeral 10 is employed to generally designate a wrench embodying the invention. This wrench is shown to comprise a body portion 11, formed from a pair of opposed parts 12 which, by reason of flanged edges, cooperate to produce a hollow handle 13. Suitable pins or rivets 14 and 16 secure these parts together. The upper end of the body portion takes the form of a pair of spaced wings 17, each wing having forward and rearward extensions 18 and 19.

A swingable jaw 21 is located between the wing extensions 19 and secured for pivotal movement by a pin 22. One end of the jaw 21 terminates in a lug 23 that, during pivotal movement of the jaw, swings into or out of the space between the wings. The other end of this jaw is formed with a head 24. The inner edge of this head is provided with sets of teeth 26 and 27, arranged at an angle to each other such as to adapt the jaw to engagement with parts of different size. The inner edge of the hub or central portion 28 of the jaw is formed with a series of teeth 29, the lowermost tooth being substantially aligned with the pin 22. From this point, the hub curves inwardly to form the lug 23. A spring 31 is mounted in the hollow body portion 11. This spring, for convenience, may be formed from a piece of U-shaped spring wire, the closed end 32 bearing against the lug 23. The spring has a loop 34 through which pin 16 projects. The free ends 36 of the spring bear against the inner edges of the sides of the body 11.

Located between the wing extensions 18 is the other jaw of the wrench which takes the form of a wheel 37 that is rotatable about a fixed pivot 38. The circumferential edge of this wheel is formed with a series of teeth 39 which are of a shape and size to mesh with the teeth 29 of the hub of the jaw 21.

To operate, the handle 13 is placed in the palm of the hand and closely gripped by the fingers. The operator's thumb is then pressed against the edge 41 of the lug 23 and, by the application of pressure, the lug is pushed inwardly of the body of the wrench, thus swinging the head of the jaw outwardly to an extent required to space the jaws for entrance of the part to be gripped. This movement of the jaw is against the tension of spring 31 and, as soon as the thumb releases pressure on the lug 23, jaw 21 swings into engagement with the part, causing it to bear against the teeth of the wheel 37. All self-gripping wrenches must be operated in one direction.

Consequently, when a wrench handle is swung to the left, as viewed in Figs. 1 and 4, the head of the swingable jaw 21 tends to move into pressure engagement with the part with which it is engaged. Any movement in this direction of this jaw, due to the geared connection between it and the wheel 37, causes said wheel to attempt to turn slightly in the opposite direction and thus the gripped part is urged into engagement with all of the teeth of the movable jaw, this urging continuing as long as pressure on the handle is applied in the direction mentioned. After the part has been turned to a desired extent, the operator may depress the edge 41 of the lug, thus releasing the grip of the swingable jaw and enabling removal of the wrench from the part.

Inasmuch as the wheel 37 rotates to force the part into tight engagement with the movable jaw, it is contemplated that the teeth thereof may be subjected to greater wear than the teeth of the swingable jaw. Also, it is evident that only a few of the teeth of the wheel 37 engage a rounded part, whereas many more teeth of the swingable jaw function during gripping the same part. At such time, in the use of the wrench, as the teeth of the wheel 37 become somewhat worn or dulled to the extent that they provide an insufficient grip, it is possible to swing the movable jaw into an extreme opened position, such as illustrated in Fig. 5. The jaw will remain in this position due to the dead center position of the spring 31. In this position of the swingable jaw, the teeth 29 of the hub 28 have moved away from the teeth of the wheel 37 and this wheel is now free to be rotated to an extent that when the jaws are brought into relatively operative position again, another series of teeth 39 will serve to engage a part located between the jaws. It will be understood that the wear of teeth 39, although enough to effect the gripping qualities, is insufficient to impair engagement with the hub teeth 29.

In the manufacture of wrenches of the type to which the invention relates, it is not only necessary to provide a strong or rugged wrench, but also one that can be inexpensively manufactured from material that requires comparatively little processing. Many wrenches are forged and this process is believed to be more expensive than the process of forming parts by stamping from sheet material and assembling several parts thereof to give desired proportions and strength. To this end, applicant discloses a modification of his invention, as shown in Figs. 6 to 8, inclusive. Herein the body portion 11, wings 17 and wing extensions 18 and 19 are identical with the structure of the corresponding parts already described. A swingable jaw 42 is of three parts or layers, the outer parts 43 being formed with identical heads 44 and having their inner edges fitted or formed with sets of teeth 46 and 47. Beyond the jaw pivot 22, parts 43 are formed with identical lugs 48. Between the parts 43 is located a further jaw part 49 which, with the exception of teeth 46 and 47 and a hub portion 51, is co-extensive with said outer parts. The hub portion 51 provides a gear segment having teeth 52.

Parts 43 and 49 may be made into a unit to form the entire jaw 42 by means of suitably located securing pins or rivets 53. Carried by the pin 38, between the wing extensions 18, is a three part wheel 54. The outer parts 56 of this wheel are identical and include circumferential teeth 57. The intermediate part 58 of this wheel is of somewhat lesser diameter and is formed with

teeth 59 which mesh with the teeth 52 of the movable jaw 42. The three parts of the wheel are secured together by pins or rivets 61. Operation of this modified wrench is similar to operation of the wrench first described.

Although applicant has shown and described only two modifications of his invention, it will be understood that variations of the structure by which to adapt the invention to wrenches of different proportions may be made and are contemplated insofar as such variations are within the scope of the annexed claims.

Having thus set forth my invention, what I claim as new and for which I desire protection by Letters Patent is:

1. A wrench comprising a handle, pairs of extensions rigid with one end of said handle, a first jaw in the form of a wheel mounted for rotation about a fixed pivot between one pair of said extensions, a second jaw, one end portion of said second jaw being mounted on a fixed pivot between another pair of said extensions, a spring normally urging said second jaw into a position of close proximity with said first jaw, and meshed teeth on said jaw, said teeth effecting rotation of said first jaw when the pivotal position of said second jaw is altered.

2. A wrench comprising a handle, pairs of extensions rigid with one end of said handle, a first jaw in the form of a wheel mounted on a fixed pivot between one pair of said extensions, a second jaw, one end portion of said second jaw being mounted on a fixed pivot carried by another pair of said extensions, meshed teeth on said jaws, said teeth effecting rotation of said wheel when the pivotal position of said second jaw is altered, a spring normally urging said second jaw into close proximity with said wheel, and finger actuated means for pivoting said second jaw into an extended operative position against tension of said spring.

3. A wrench comprising a handle, pairs of adjacent extensions rigid with and extending from one end of said handle, a first jaw, said jaw taking the form of a toothed wheel and being mounted for rotation about a fixed pivot carried by one pair of said extensions, a second jaw, a fixed pivot carried by another pair of said extensions and mounting said second jaw, teeth on said second jaw adjacent one end thereof, said teeth normally meshing with the teeth of said wheel and operable to effect rotation of said wheel when said second jaw is moved about its pivot, and finger actuated means for pivoting said second jaw.

4. A wrench comprising a handle, pairs of adjacent extensions rigid with and extending from one end of said handle, a first jaw, said jaw taking the form of a toothed wheel and being mounted on a fixed pivot carried by one pair of said extensions, a second jaw, said second jaw being mounted adjacent one end thereof on a fixed pivot for movement between another pair of said extensions, teeth on said second jaw adjacent said end, said teeth normally meshing with the teeth of said wheel and operable to effect rotation of said wheel when said second jaw is pivoted, a lug on said second jaw, a spring carried by said handle and engaged with said lug and normally urging said second jaw into close proximity with said wheel, said lug being manually operable to pivot said second jaw into an extended position with respect to said wheel and against the tension of said spring.

5. A wrench comprising a handle, a pair of

adjacent extensions rigid with and extending from one end of said handle, a first jaw, said jaw taking the form of a toothed wheel and being mounted on a fixed pivot carried by one of said extensions, a second jaw, said second jaw being mounted intermediate its ends upon a fixed pivot carried by another of said extensions, teeth on said second jaw adjacent the pivot thereof, said teeth normally meshing with the teeth of said wheel and operable to effect rotation of said wheel when said second jaw is moved about its pivot, a lug forming an extension of an end of said second jaw, a spring carried by said handle engaged with said lug and normally urging said second jaw into proximity with said wheel, said second jaw being pivotally movable to a position to render said spring ineffective and disengage the teeth of said wheel from the teeth of said second jaw.

6. A wrench comprising a handle, pairs of extensions integral with one end of said handle, a first jaw, said jaw taking the form of a wheel mounted on a fixed pivot between one pair of said extensions, gripping teeth on the circumferential edge of said wheel, a second jaw, fixed piv- 20 15 25

tal means mounting said second jaw between another pair of said extensions, gripping teeth on one end of said second jaw, further teeth on an intermediate portion of said second jaw engaged with the teeth of said wheel and being effective to rotate said wheel during pivotal movement of said second jaw, spring means operable to urge the gripping teeth of said second jaw into proximity with the teeth of said wheel, and finger actuated means for moving said second jaw into an extended position with respect to said wheel and against tension of said spring means.
